CALCULATING MACHINE

William Ball, Wallington, England, assignor, by direct and mesne assignments, to British Adding and Calculating Machines Limited, London, England

Original application May 31, 1930, Serial No. 458,629. Divided and this application August 13, 1931, Serial No. 556,836. In Great Britain and France April 14, 1930

7 Claims. (Cl. 235—133)

This invention relates to calculating machines and is a division from application Serial No. 458,629 filed 31st May, 1930, Patent No. 1,930,870, granted October 17, 1933, wherein differentially 5 geared actuating and setting mechanism is employed for the totalizer wheels, that is mechanism wherein the actuating member is differentially movable with respect to the associated setting element.

10 Such actuating and setting mechanism is particularly advantageous inasmuch that transfer between adjacent totalizer wheels can be effected through the actuating and setting mechanism associated with the totalizer wheel of higher designation, the mechanism of each denominational section including normal stationary transfer members which may be displaced for transfer, either during or subsequent to the setting of the totalizer wheels in any one cycle of the main 15 shaft during its operation.

It is often necessary, however, in machines of the kind above referred to, to take a clearing or spacing stroke between successive cycles in order to restore displaced transfer members, so as to 20 avoid an incorrect setting of the totalizer wheels, when it is required to accumulate the next item thereon, and it is the main object of the present invention to avoid the necessity of such clearing strokes.

25 30 According to the invention, means are provided which are operable from the main shaft of the machine to reset displaced transfer members during each cycle of the main shaft, together with means which latch the members in the reset 35 position. By this arrangement the actuating mechanism is completely restored after each cycle of the main shaft so that it is unnecessary to take a clearing stroke when changing from addition to subtraction or total taking in successive cycles 40 while operating the machine.

The invention will be better understood with reference to the following detailed description, taken in conjunction with the accompanying 45 drawings, in which the invention is shown applied to the form of calculating machine, illustrated in the parent case, only those figures being shown which are deemed necessary for a complete understanding of the structure claimed. It 50 will be understood, however, that the features of this invention are not limited specifically to the adding and subtracting form of machine shown.

In the drawings,

Fig. 1 is a detail part perspective view showing 55 more particularly the means for resetting the

transfer rack of one calculating unit, the non-essential parts being omitted for clearance;

Fig. 1^a is a fragmentary figure showing in side elevation the elements shown in perspective at the right hand side of Fig. 1;

Fig. 2 is a view from the left of a calculating unit detached, the column showing nine numeral keys in addition to the column release key at the extreme right hand end and corresponding to one of the pounds columns in the machine;

Fig. 3 is a corresponding view from the right of the same unit with type bar omitted and the totalizer wheel disengaged from the actuating rack to clearly indicate the normal position thereof when the unit is mounted in the machine.

Referring now to the drawings, the machine comprises a number of detachable calculating units 12 each of which consists of a stretcher plate 28 carrying a key column including numeral keys 32 and a column release key 32a which in the normal position shown is depressed to engage the first abutment on the setting rack 58 herein-after described, the arrangement being such that when a numeral key is depressed the column release key is released to permit the setting rack to move to engage the depressed numeral key. The operation of the numeral and column release keys is clearly described in the parent case.

Each calculating unit is provided with a totalizer wheel 20, and differentially geared actuating and setting mechanism for the totalizer wheel.

The totalizer wheel 20 is carried on a spindle 89a mounted on the bell crank 90 and moving within a slot 90a in the stretcher plate 28. The bell crank 90 is pivoted to the stretcher plate 28 at 91, and is arranged for actuation by a transverse bail 140 which engages a slot 92 in said bell crank 90 to throw the totalizer wheel 20 into engagement with the actuating rack 56—hereafter referred to—during its return stroke for addition, the wheel 20 being normally held out of engagement with the rack 56 and its setting being held by a lug 93 which projects from the left face of the stretcher plate 28 and forms a locking and alignment pawl by engaging the teeth of the pinion 68 of the totalizer wheel 20 (see Figure 3).

The spindle 89a normally abuts against the top face of the slot 90a and upon the bell crank 90 being operated by the bail 140 moves until it abuts against the lower face of the slot. This slot, therefore, determines the radial movement of the bell crank arm carrying the totalizer wheel 20 and the mesh of the pinion 68 with the actuating rack. The mechanism by which the bail 140 is

actuated may be found in the parent case and is not herein described as it does not form part of the present invention.

With reference now to the differentially geared actuating and setting mechanism for the totalizer wheel 20, the stretcher plate 28 is provided with a number of slots 51, 52, 54, 44a and 44b, which form guides for mounting the mechanism, which comprises an upper normally movable rack 53 provided with headed pins 69 riding in the slots 51, 52, a normally stationary lower rack 57, hereinafter referred to as a transfer rack, provided with headed pins 44 riding in the slots 44a and 44b a linearly movable pinion 55 engaging with both the upper rack 53 and the transfer rack 57, the pinion being carried on a pin 55a riding in the slot 54, the actuating rack 56 formed with a slot 66 engaging with a headed pin 67 mounted on the stretcher plate 28, the rack 56 being mounted at its forward end on the pin 55a of the pinion 55, and a setting rack 58 pivoted at 59 on the upper rack 53.

With this arrangement it will be seen that the movement of the upper rack 53 is in all cases double that of the pinion 55 when the transfer rack 57 is stationary, and consequently double the movement of the actuating rack 56, and in this manner a well spaced keyboard may be attained, and, as described hereinafter, transfer may be effected through the actuating mechanism during the setting of the totalizer wheels 20.

The free end of the setting rack 58 is provided with a stub 60 arranged to ride in an inclined guide slot 61 formed in the body 62 of the actuating rack 56, the arrangement being such that during the movement of the differentially geared mechanism from the zero position illustrated, the setting rack rises towards the keyboard by means of the guide slot 61 and the differential movement between the actuating rack 56 and the upper rack 53, it being understood that since the upper rack 53, and therefore the setting rack 58, gains on the actuating rack 56, the stub 60 and the rear end of the setting rack 58 will be caused to ride up the inclined slot 61 in the actuating rack 56.

Along the setting rack 58 are provided a number of abutments 63 which are arranged so that the forward or right hand abutment 63, seen in Figure 2, co-operates with the 0 or column release key 32a, the second abutment with the 1 key, and so on, the last or left hand abutment co-operating with the 8 key, and the end of the slot 61 in the actuating rack 56 being employed as the final or 9 abutment corresponding with the full travel of the setting rack 58, and thereby eliminating the necessity for a further abutment on such setting rack, although, if desired, of course, such an abutment could be provided to co-operate with the stub of the 9 key.

64 is a coil spring connected between the end of the setting rack 58 and a pin 65 on the actuating rack 56, which spring actuates the transfer rack 57 for addition transfer and also renders the differentially geared mechanism substantially self-acting by reason of the fact that the spring is normally in tension as will be explained later.

It will be understood that for a pence column twelve keys will be provided, and correspondingly eleven or twelve abutments 63, according to whether the end of the slot 61 is employed as a limit or not, and that the number of keys and co-operating abutments is adapted to the requirements of each particular case, the particu-

lar unit illustrated being one of the pounds columns of the pounds, shillings and pence machine illustrated as the preferred embodiment.

The elements of the differentially geared actuating and setting mechanism are shown in the normal or zero position, the 0 or column release key 32a at the right of the column being depressed and engaging its abutment to maintain the setting rack 58 and the remainder of the mechanism therein.

Movement of the above mechanism after a key 32 has been depressed, is controlled from the main operating shaft 1 of the machine through an operating member constituted by a rocker 70 pivoted to a shouldered pin 71 at the foot of the stretcher plate 28, and having three arms, the first 72 being provided with an anti-friction roller 73 which when the unit is assembled in the machine abuts against a control arm 74 on the main operating shaft 1, the roller, if permitted, tending to follow the arm 74 under spring action as hereafter explained during the initial stroke of the handle 4, which, as customary, is in the direction of the arrow A in Fig. 2.

A second arm 75 forms the operative connection with the pinion 55 of the mechanism, being formed with a slotted end 76 in which rides a pin 77 carried by a link 78 in turn carried on the pivot of the pinion 55.

A pin 79 on the arm 75 and a second pin 80 on the link 78 are connected by a coil spring 81 which, during operation of the machine, maintains the pin 77 to the right of the slotted end 76 as shown, and ensures that the setting rack 58 is maintained in the normal position during the depression of the column release keys towards the end of the ultimate return stroke of the main shaft, as is explained in the parent case. It will be noted that the position of the rocker 70 and of the pin in the slotted end 76 thereof as shown in the drawings is that when the handle 4 has been moved slightly forward without a key being depressed. Thus, if the handle is restored the slotted end would move across the pin 77 until the latter abuts against the opposite end to that shown, this slotted end therefore providing a lost motion to ensure proper zeroizing and to eliminate spacing strokes, as hereafter explained. It will be further noted, however, that when the pin 77 is at the opposite end of the slotted end 76, the spring 81 is under tension, thus enabling the lost motion to be taken up upon the handle again being moved forward.

A third arm 82 completes the rocker 70, and is provided with an anti-friction roller 83 which cooperates with an oscillating lever 84 pivoted to the stretcher plate 28 at 85 to actuate a type bar of the printing mechanism described in the parent case.

To enable the roller 73 to follow the arm 74 and the differentially geared actuating and setting mechanism to be substantially self-acting, the spring 64, in the normal position of the differential mechanism, is under tension so that when the setting rack 58 is unlocked, by releasing the column release key 32a, and the handle 4 is moved forward, the setting rack 58, the actuating rack 56 and the pinion 55, together with the rocker 70 automatically move rearwardly due to the tension in the spring 64, the roller 73 thus following the arm 74, and the rate of the movement of the parts being governed by the movement of the handle. During the return stroke of the handle 4, the arm 74 abuts against the roller 73 to move the rocker 70 forwardly and

thereby restores the actuating mechanism against the tension of the spring 64. To facilitate the automatic movement of the parts and also to cause movement of the transfer rack 57 for a subtraction transfer as subsequently described, a further tension spring 64a is provided connected between points on the stretcher plate 28 and the rocker 70, or the spring 64a, may be used in place of the spring 64.

Assuming that, in place of the column release key 32a shown depressed in Figure 2, the 8 numeral key is depressed and the operating handle 4 turned in the direction of the arrow A, the setting rack 58 and the actuating rack 56 will move to the left (Figure 2) the rocker 70 turning in an anti-clockwise direction as the arm 74 rotates away from the roller 73 until the respective abutment 63, i. e. the left hand one, engages the stub of the 8 key, when the further movement of the actuating rack 56 will be arrested and the arm 74 will leave the roller 73.

In this position the actuating rack 56 will have moved a space equivalent to eight facets of the totalizer wheel 20, and if the wheel 20 through its pinion 68 be then engaged with the actuating rack 56 and the operating shaft 1 returned to its initial position, the totalizer wheel would show a reading corresponding with the item set up in the key column, i. e. the number 8.

The engagement operations of the totalizer wheels 20 are fully described in the parent case.

When a totalizer wheel is passing from 9 to 0 in addition and 0 to 9 in subtraction, it is necessary to transfer one digit to or from the next wheel of higher denomination, and to do this each unit is provided with addition and subtraction transfer mechanisms, 94 and 95, respectively, each comprising a pair of bell crank levers mounted on a common pivot 96, see Fig. 3.

Each totalizer wheel 20 is provided at its left side see Fig. 2 with a pair of lugs 97 and 98, herein called the addition transfer lug and the subtraction transfer lug respectively. These lugs cooperate with the transfer mechanisms 94 and 95 of the left adjacent unit 12, i. e. the unit of next higher denomination, so that on a totalizer wheel 20 changing from 9 to 0 during addition, or from 0 to 9 during subtraction, the respective transfer mechanisms 94 or 95 of the next higher denomination is actuated to add or subtract one, as the case may be to or from its wheel 20.

This transfer is effected, as previously mentioned, through the medium of the lower and normally stationary transfer rack 57 of the next higher denomination, by the mechanism now to be described, which is substantially in accordance with that disclosed in the specification of my U. S. Patent No. 1,838,209.

The addition transfer mechanism 94 of each unit, which it will be more convenient to describe first, includes a three-armed bell crank 100 having one arm 100a approximately at right angles to two forking arms 100b, 100c, and pivoted at 96 to the right face of the stretcher plate 28, the arm 100a carrying a pin 101 projecting through a slot 102 in the stretcher plate 28 and engaging a co-operating notch 103 in the transfer rack 57 see Fig. 2.

Normally, the pin 101 engages the notch 103 and locks the transfer rack 57 in its neutral mid position. When an addition transfer is to be effected, the addition transfer lug 97 on the totalizer wheel of the next lower denomination engages the shorter arm 100c as it passes from 9 to 0 and rocks the bell crank 100 so that the

pin 101 moves down the slot 102 and out of engagement with the notch 103, whereat by movement of pinion 55 by the rocker 70 and under the action of the spring 64 Fig. 2, the transfer rack 57 moves forwardly i. e. to the right as viewed in Figs. 1 and 2 and permits the actuating rack 56 to turn the totalizer wheel 20 one tooth space in the direction of addition, whereby the next higher numeral reading is shown thereon.

The subtraction transfer mechanism 95 is also mounted on the common pivot 96 and includes a second bell crank 104 carrying a pin 105 passing through a slot 106 in the stretcher plate 28, and engaging a cooperating slot 107 formed in the transfer rack 57.

The slot 107 includes a pair of offset lateral branches 108, 109, the pin 105 normally lying at the head of the slot 107 adjacent the branch 108 and in abutment with the wall 108a terminating this branch, so that on the locking pin 101 of the addition transfer being removed from its notch 103, the transfer rack 57 is permitted to move by reason of the branch 108 passing along the pin 105, the dimensions of this branch being such as to permit a movement of the transfer rack 57 corresponding to one tooth space of the actuating rack 56.

As shown in Figure 3, two retaining pawls 100d and 100e are provided for retaining the transfer mechanisms 94 and 95 in their operative positions when either addition or subtraction transfer is effected. The retaining pawl 100d is pivoted at 100f to the stretcher plate, while the retaining pawl 100e is pivoted, as shown, to a lug 104a on the right-hand arm of the bell crank 104 of the subtraction transfer mechanism 95, the bell crank 100 of the addition transfer mechanism 94 being provided with a pair of outstanding lugs 100g and 100h formed with ratchet teeth for engaging respectively with the retaining pawls 100d and 100e. The pawls 100d and 100e are maintained in engagement with their respective ratchet teeth by means of springs 100i and 100j connected between points on the pawls and the bell crank 100, the spring 100j also serving to bring the subtraction transfer 95 into a condition for subtraction transfer when the bell crank 100 is rocked by a bail 110 actuated from the subtraction key as described in the parent case.

When the machine is set for addition, the addition transfer mechanism 94 is as shown in Figure 3, and thus, when the bell crank 100 is rocked for an addition transfer, the retaining pawl 100d drops into the first of the ratchet teeth on the lug 100g to maintain the bell crank 55 in its rocked position.

When the machine is conditioned for subtraction, the bail 110 engaging with the arm 100b of the bell crank 100 is caused to rock the latter about the pivot 96, so that the pin 101 moves down the slot 102, and by reason of the spring 100j the bell crank 104 of the subtraction transfer mechanism 95 is simultaneously rocked about the pivot 96, thereby moving the pin 105 past the branch 109 down to the bottom of the slots 106 and 107. Thus, although the transfer rack 57 has been released by the pin 101, it is still maintained in its normal position by reason of the pin 105 engaging with the transfer slot 107 in the transfer rack.

Since the bell crank 104 of the subtracting transfer mechanism has been rocked about the pivot 96 as explained above, the right-hand arm of the bell crank will be in a position to engage the transfer lug 98 of the next lower denomina- 75

tional totalizer wheel 20. When, therefore, a subtraction transfer is to be effected, which is when the said wheel is passing through 0 to 9, the lug 93 engages with the right-hand arm of 5 the bell crank 104 to rock the latter and bring the pin 105 opposite the branch 109 whereby the transfer rack may be permitted to move to the left, the branch 109 running along the pin 105 until it is engaged by the wall 109a so that the 10 actuating rack is moved one tooth space in the direction of subtraction. This movement is delayed until after the setting of the totalizer wheels so as to permit printing to take place first, by a transverse bail 320 carried by arms 321 15 pivoted to the side frames of the machine, the bail 320 being arranged by means of spring 322a to co-operate with elongated notches 323 formed on the lower edge of each transfer rack 57 where in its normal or mid position it projects beyond 20 the limits of the stretcher plate 28.

Mounted on the main shaft 1 is a full stroke 25 pawl quadrant 343 provided with a cam track 324, which, towards the end of the forward stroke, engages with the end of the bail 320 to rock the arms 321 downwardly, thereby tensioning the springs 322a and bringing the bail 320 out of engagement with the notches 323, so that any transfer racks which have been set for transfer are shot to take one from the reading on their respective 30 totalizer wheels 20, it being understood, however, that the cam face 324 delays the release of the bail 320 from the notches 323 until after the printing is effected.

It will be noted here, that for a subtraction 35 transfer the transfer racks are moved rearwardly to effect the transfer by the spring 64a, which, upon the racks 57 being released by the bail 320, pulls the rocker 70 to the left. The upper rack 53 and the setting rack 58 are maintained stationary in the set position by the tension in the spring 64, so that the left hand movement of the rocker 70 and consequently of the pinion 55 and actuating rack 56 causes the transfer rack 57 to move to the rear with a 2:1 movement with respect to the actuating rack 56, until the pin 105 abuts against the right hand end of the branch slot 109, when one will have been subtracted from the totalizer wheel 20.

Further it will also be noted that when a subtraction transfer has been initiated, the pawl 100e will be engaging with the ratchet tooth on the lug 100h, and since the pawl 100d is already engaging with the second tooth on the lug 100g by reason of the rocking of the bell crank 100 by the bail 110, both the subtraction and addition transfer mechanisms will be retained in operative position, so that the transfer rack can move immediately it is freed by the bail 320.

It will be understood that the actuating rack 56 being in engagement with the totalizer wheel 20 during the forward stroke i. e. to the left, as seen in Figure 2 only for subtraction, and during the rearward stroke i. e. to the right, as seen in Figure 2 only for addition, the resetting of the transfer rack 57 at the end of the return stroke for addition only will not affect the totalizer wheel 20, since it is out of engagement with the actuating rack 56, as is explained in the parent case. The means employed for resetting the transfer rack to normal will also be explained subsequently, but it will be noted that when the transfer rack has effected a subtraction transfer, i. e. moved to the left during the forward stroke, it is brought back to its normal position by movement of the pinion 55 during the return stroke,

and is retained in said position by the left-hand wall of the branch slot 107 abutting against the pin 105, until such time as it is latched by the pin 105 or 101.

It may be mentioned here, however, that when 5 the totalizer wheel 20 is brought out of engagement with the actuating rack 56, either at the end of the forward stroke for subtraction, or towards the end of the return stroke for addition, as is explained in the parent case, the consequent 10 rocking of the bell crank 90 causes the pin 109k thereon to abut against the pawl 100d, if transfer has taken place.

If the machine is set for addition, this will 15 disengage the pawl 100d from the first tooth on the lug 100g, and thus allows the bell crank 100 to be restored by the tension in the spring 100i. On the other hand, if the machine is set for subtraction, that is the pawl 100d is engaging with the second of the ratchet teeth on the lug 20 100g and a subtraction transfer has been effected, in which case the pawl 100e will be engaging with the ratchet tooth on the lug 100h, and an outstanding lug 100l on the pawl 100e will be engaging with the pawl 100d, then upon the pin 109k of the bell crank 90 abutting against the pawl 100d, the pawl 100e will be disengaged from its ratchet tooth, and if the bail 110 has been restored, both transfer mechanisms 94 and 95 25 will be restored to normal, as shown, through the 30 tensions in the springs 100i and 100j respectively and the pin 101 on the bell crank 100 will consequently engage in the notch 103 in the transfer rack 57 to lock the same.

Thus when the transfer rack 57 is restored during 35 the return stroke of a subtraction cycle, the bell crank 104, due to the pawl 100e being disengaged, will rock in an anti-clockwise direction by the tension in the spring 100j, so that the pin 105 moves down to the bottom of the slot 106 and the 40 slot 107 in the transfer rack 57 to lock the latter in normal position and condition the bell crank 104 for effecting a subtraction transfer on any subsequent stroke, when necessary.

In regard to both addition and subtraction 45 transfers it may be mentioned that when the machine is set for subtraction and a subtraction transfer is effected at the end of the forward stroke as has been described, the transfer racks 57 are moved to the normal position during the 50 return stroke and are latched in the said position firstly by the pins 105, on the bell cranks 104, moving down to the bottom of the branches 107 in the transfer racks 57, the pawls 100e being disengaged by the totalizer wheels being out of mesh, 55 and subsequently the transfer racks are locked in said normal position by the restoration of the bell cranks 100 to engage the pins 101 in the notches 103. It may be noted that when the transfer racks are moved to the normal position during the return stroke, the bail 320 snaps back into the notches 323 by the tension in the springs 322a, and further that the notches 323 permit the transfer racks to move to the right for addition transfer.

If the machine is set for addition, however, and an addition transfer has been effected, then since 60 for addition, the totalizer wheels are in mesh on the return stroke, the transfer racks 57 which have been shot will remain in the shot position, i. e. to the right by the tension in the springs 64. Consequently, it is necessary to restore such racks to normal if the whole of the differently geared 70 actuating and setting mechanism is to be in nor- 75

mal position after each cycle of the main operating shaft 1.

To thus ensure complete and automatic restoration of the actuating mechanism at the end 5 of each complete stroke of the shaft 1, and thereby eliminate the necessity for spacing strokes, the operating shaft 1 is provided with a series of short arms 330. Fig. 1.

When the setting racks 58 have been restored 10 to their normal position towards the end of the return stroke of the handle 4, in addition, and just after the totalizer wheels 20 have been brought out of mesh with the actuating racks and the column release keys have been depressed 15 to lock the setting rack 58 and the rack 53, the short arms 330 come into abutment with pins 331 on the transfer racks 57 which have been displaced to the right for transfer. Further movement of the main shaft 1 towards its normal 20 position thus causes these racks to be replaced into their mid positions and restoration of the actuating racks, the transfer racks being automatically latched by the pins 101 of the transfer mechanism.

25 Thus, whether the machine is set for addition or subtraction, the whole of its actuating and setting mechanism is restored at the end of each cycle of the main shaft in one operation.

From the foregoing it will be seen that by this 30 invention very simple and effective means have been provided, for resetting displaced transfer racks during each cycle of the main shaft of the machine, thereby avoiding the necessity of the customary clearing stroke between each cycle.

35 Although the invention has been shown and described with reference to an adding and subtracting machine, it will be understood that it is equally well applicable to a machine which adds only and further that modifications in the constructional details can be made by those skilled in the art without in any way departing from the scope of the appended claims.

What I claim is:

1. In a calculating machine, the combination 45 with totalizer wheels, each having an upper rack, a setting rack connected thereto, a normally stationary transfer rack and a pinion engaging with both of said upper and transfer racks, whereby movement of said pinion moves the upper and setting racks by an amount equal to twice the linear movement of the pinion, of means for moving the transfer rack out of its normal position in one direction to effect a transfer, a main operating shaft, an operative connection between said main shaft and said pinion, and abutment means carried by said operating shaft so as to reset the transfer rack after said rack has been displaced to effect a transfer, and means for latching said transfer rack in the reset position.

2. In a calculating machine, the combination 60 with totalizer wheels, each having an upper rack, a setting rack connected thereto, a normally stationary transfer rack and a pinion engaging with both of said upper and transfer racks, whereby movement of said pinion moves the upper and setting racks by an amount equal to twice the linear movement of the pinion, of spring means for moving the transfer rack out of its normal position to effect a transfer, a main operating shaft, an operative connection between the operating shaft and said pinion, and abutment means carried by said operating shaft so as to reset the transfer rack after it has been displaced

to effect a transfer, and means for latching said transfer rack in the reset position.

3. In a calculating machine, the combination 5 with totalizer wheels, each having an upper rack, a setting rack connected thereto, a normally stationary transfer rack and a pinion engaging with both of said upper and transfer racks, whereby movement of said pinion moves the upper and setting racks by an amount equal to twice the linear movement of the pinion, of co-operating 10 addition and subtraction transfer levers operable by the totalizer wheels, said addition transfer levers engaging in notches in the transfer racks so as to latch the latter in the initial position, and said subtraction levers engaging in three- 15 armed slots in the transfer racks, means for moving each rack for addition transfer, said movement being governed by the first arm of the slot, means for moving the rack for subtraction transfer, said movement being governed by the second 20 arm of the slot and means for moving the subtraction lever into the third arm of the slot when the machine is set for subtraction to hold said rack until released for transfer, a main operating shaft, an operative connection between the main 25 shaft and said pinion, and abutment means movable with the main shaft so as to reset the transfer rack into the initial position at the end of the return stroke of said shaft.

4. The structure of claim 3 and including abut- 30 ments on each transfer rack formed by the third arms of said three-armed slots, whereby said racks are prevented from over-shooting the initial position when being reset after a subtraction transfer.

35 5. In a calculating machine, the combination with totalizer wheels, each having an upper rack, a setting rack connected thereto, a normally stationary transfer rack and a pinion engaging with both of said upper and transfer racks, whereby 40 movement of said pinion moves the upper and setting rack by an amount equal to twice the linear movement of the pinion, a main operating shaft, and an operative connection between said main shaft and said pinion, of addition transfer 45 levers operable by the totalizer wheels and normally engaging in notches in the transfer racks so as to latch the latter in the initial position, abutment means carried by the main shaft so as to reset displaced transfer racks into the initial 50 position at the end of the return stroke of said shaft, and means for causing operated addition transfer levers to return to their latching position, whereby said reset racks are relatched.

6. In a calculating machine, the combination 55 with totalizer wheels, each having an upper rack, a setting rack connected thereto, a normally stationary transfer rack and a pinion engaging with both of said upper and transfer racks, whereby movement of said pinion moves the upper and setting racks by an amount equal to twice the linear movement of the pinion, of co-operating 60 addition and subtraction transfer levers operable by the totalizer wheels, said addition transfer levers engaging in notches in the transfer racks 65 so as to latch the latter in the initial position, and said subtraction levers engaging in three-armed slots in the transfer racks, means for moving each rack for addition transfer, said movement being governed by the first arm of the slot, 70 means for moving the rack for subtraction transfer, said movement being governed by the second arm of the slot, and means for moving the subtraction lever into the third arm of the slot when the machine is set for subtraction to hold said 75

rack until released for transfer, a main operating shaft, and an operative connection between the main shaft and said pinion, of holding means engaging the transfer racks so as to hold said transfer racks from being displaced, means for releasing said holding means subsequent to the setting of the totalizer wheels, whereby transfer is delayed, abutment means carried by the main shaft so as to reset displaced transfer racks at the end of the return stroke of said main shaft, and means for causing operated addition transfer levers to return to their latching position, whereby said reset racks are relatched.

7. In a calculating machine, the combination with totalizer wheels, each having an upper rack, a setting rack connected thereto, a normally stationary transfer rack and a pinion engaging with both of said upper and transfer racks, whereby movement of said pinion moves the upper and setting racks by an amount equal to twice the linear movement of the pinion, of co-operating addition and subtraction transfer levers operable by the totalizer wheels, said addition transfer levers engaging in notches in the transfer racks so as to latch the latter in the initial position,

and said subtraction levers engaging in three-armed slots in the transfer racks, means for moving each rack for addition transfer, said movement being governed by the first arm of the slot, means for moving the rack for subtraction transfer, said movement being governed by the second arm of the slot and means for moving the subtraction lever into the third arm of the slot when the machine is set for subtraction to hold said rack until released for transfer, a main operating shaft, and an operative connection between the main shaft and said pinion, of a holding bail engaging in notches in the transfer racks so as to hold said transfer racks from being displaced in one direction, the notches being formed to permit displacement of the transfer racks in the opposite direction, means for releasing said holding bail subsequent to the setting of the totalizer wheels, whereby transfer is delayed, abutment means carried by the main shaft so as to reset displaced transfer racks at the end of the return stroke, and means for causing operated addition transfer levers to return to their latching position, whereby said reset racks are relatched.
